CLAIM

The ornamental design for a support stand for playground globe, as shown and described.

DESCRIPTION

FIG. 1 is a top front perspective view of a support stand for playground globe showing my new design; the broken lines showing a globe is for illustrative purposes only and form no part of the claimed design;

FIG. 2 is a front elevational view thereof; the rear elevational, right side elevational and left side elevational views being identical;

FIG. 3 is a top plan view thereof; and,

FIG. 4 is a bottom plan view thereof.
